UNITED STATES PATENT OFFICE.

VERNON F. JEWETT, OF PORTLAND, OREGON.

FAIR LEADER.

Application filed August 26, 1922. Serial No. 584,530.

To all whom it may concern:

Be it known that I, VERNON F. JEWETT, a citizen of the United States, residing at Portland, county of Multnomah, in the State 5 of Oregon, have invented a new and useful Fair Leader, of which the following is a specification.

My invention relates to devices for guiding the line to the drum on logging engines 10 and winding engines of any character that require a leadblock, rollers or other devices to guide a line onto a winding drum, and the invention consists in the improved construction and devices as shown in the accompanying 15 drawings, and described in this specification and the claims appended thereto, which disclose a preferred application of my new invention. The said drawings are a part of this specification.

Fig. I is a side elevation of my new fairleader with parts broken away to better disclose its construction. Fig. II is a front elevation of my new fairleader and Fig. III is a sectional view taken on the line III— 25 III, Fig. II. Fig. IV is a side elevation showing a hauling rope making an angle in a vertical plane and pulling at 45° below horizontal. Fig. V is a front elevation with the hauling rope leading down 45° from a 30 horizontal plane and 22½° out of the vertical plane. The purpose of these illustrations being to show that the fairleader will assume a position giving a fair lead from the fairleader to the winding drum and 35 from the load to the fairleader, regardless of the position of the load with relation to the said winding drum.

A pedestal 20, comprising a base portion 20' and a retaining ring 20'', is securely 40 anchored with a side of the retaining ring 20'', preferably parallel with the axis of a winding drum (not shown), located some distance from it.

The inner surface of the retaining ring 45 20'' (see Figs. II and III) is fashioned to the form of a zone, having approximately equal bases and adapted to contain and retain a movable member 21, having surfaces that are portions of a sphere which is 50 adapted to move freely, within desirable limits, in said retaining ring 20''. The said movable member 21, having surfaces of spherical form and adapted to fit movably within the said retaining ring 20'', comprises a carrier for two sheaves, a guide 55 sheave 22, the axis of which is coincident

with one of the axes of the said movable member 21, and a load sheave 23, the axis of which is not coincident with any axis of the movable member 21. Suitable bearings 60 for the guide sheave 22 and the load sheave 23, are shown at 22' and 23'.

It is not necessary that the movable member 21 be a complete sphere as a sufficient degree of motion within the retaining ring 65 20'' to adapt it to all desirable movements may be secured by constructing spherical shaped surfaces approximately as shown, and by providing stops as shown at 21' to prevent the movable member 21 from coming out of the retaining ring 20'' after it has been inserted.

A winding drum, not shown, will be assumed to be on the side of the fairleader indicated by the arrows in Fig. I and Fig. 75 IV and behind the fairleader in Fig. II and Fig. V, and it will be apparent to any one skilled in the art to which this invention appertains that inasmuch as the rope 24 passes through the movable member 21 80 at a point eccentric to the axis of the said movable member 21, that when a strain is applied to the rope 24, the movable member 21 will move in the retaining ring 20'' to a point where a line from the axis of the movable member 21, through the axis of the load sheave 23, will bisect the angle that is supplementary adjacent to the angle of divergence of the rope on any plane, as shown in Fig. IV, thus comprising a perfect fairleader 85 that will at all times lead a rope fair to a winding drum and from a load straight over the center of the load sheave 23 without appreciable wearing effect upon either the rope, the fairleader or the sheaves. 90

The structure as hereinbefore described and illustrated presents a means of holding the sheave 25 in the bight of the rope 24 under tension and permitting the tension on the rope 24 to influence the position of the said sheave 25 and through it the movable member 21 to bring it into a fairleading position. It will be noted that the rope 24 may move in an orbital path about the center of rotation of the movable member 100 21 in a vertical plane and through an orbital path in any other plane, thus providing the greatest possible latitude of movement, this accomplishment being rendered possible by supporting the movable fairleading structure by spherical points of contact outside of the orbit of the rope. 110

Removable wearing plates 25 are shown attached to that part of the movable member 21 with which the rope 24 will contact in swinging the said movable member 21 5 within the retaining ring 20''.

It is evident that considerable departures may be made from the construction shown in the drawings without departing from the principles of my invention. For example, 10 the retaining ring 20'' may be made of a different width and the movable member 21 may be made more nearly truly spherical, or under certain circumstances the sheaves may be dispensed with entirely and a passageway for the rope 24 be provided at a 15 point eccentric to the axis of the movable member 21 for light service.

Having thus fully disclosed my invention in a manner that will permit anyone skilled 20 in the art to which it appertains to make and use the same, what I claim as new and desire to secure by Letters Patent, is:—

1. In a fairleader, a ring member, the inner surface of said ring member fashioned 25 to form a hollow zone having two bases, each of which is of less diameter than the central portion of said zone; means for supporting said ring member; a movable member having spherical surfaces adapted to fit 30 movably within said ring member; a ropeway through said movable member at a point eccentric to the center of rotation of said movable member; plural sheave means for maintaining the relative position of a 35 rope that shall pass through said ropeway with respect to said center of rotation whereby the said rope is maintained at a predetermined distance from said center of rotation to provide leverage for rotating the 40 said movable member to a fairleading position under the influence of rope tension.

2. In a fairleader, a ring member, the inner surface of said ring member fashioned to form a hollow zone having two bases, 45 each of which is of less diameter than the central portion of said zone; a movable member having spherical surfaces adapted to fit movably within said ring member, a passageway for a rope through said movable 50 member at a point eccentric to the axis of said movable member; a sheave within said movable member having an axis coincident with one of the axes of the said movable member and acting as a guide sheave; an 55 other sheave within said movable member disposed in approximately the same plane as the first sheave and having an axis eccentric to the axis of the said movable member and purposed to act as a load sheave for a 60 rope, for the purpose specified and set forth.

3. In a fairleader, a ring member, the inner surface of said ring member fashioned to form a hollow zone having two bases, 65 each of which is of less diameter than the central portion of said zone; means for sup-

porting said ring member; a movable member having spherical surfaces adapted to fit movably within said ring member; a ropeway through said movable member at a point eccentric to the center thereof; guides 70 for said ropeway comprising a grooved load sheave having a diameter less than the radius of said movable member and so disposed therein that its grooved edge may sustain a rope at a desirable distance from 75 the center of rotation of said movable member and between said edge and said center; a guide sheave in approximately the same plane as the load sheave and adapted to hold a rope in the grooved load sheave whereby 80 the distance from the center of the rope to the center of rotation of said movable member is utilized as leverage to rotate the said movable member to a fairleading position by tension applied to a rope passing through said ropeway.

4. In a fairleader of the character described, a ring member, the inner surface of which is fashioned as a portion of a hollow sphere; a movable member of the character described, freely turnable within said ring member; a ropeway through said movable member at a point eccentric to the axis thereof; a plurality of sheaves disposed within said movable member and freely 90 turnable therein, having grooves in the rims thereof for a rope to work in and said sheaves disposed in the same plane in such a manner that the respective grooves form 95 a substantially circular ropeway at a predetermined distance from the axis of the said movable member, for the purpose specified.

5. In a fairleader adapted to automatically adjust its position according to the angle of a rope passing through it; the combination of a ring member, the inner surface of which is fashioned to form a zone having two bases which are geometrical small circles; a movable member having spherical shaped surfaces adapted to fit movably within said ring member; a ropeway through said movable member at a point eccentric to the axis of said movable member; a sheave within said movable 110 member having a grooved rim for a rope to work in; means for retaining a rope in said grooved rim at a point predeterminedly distant from the axis of said movable member and between the said sheave and the axis of said movable member whereby the movable member may be rotated to a fairleading position under the influence of rope tension.

6. In a device of the character described, 125 a fairleader comprising a fixed member that is a portion of a hollow sphere; a movable member adapted to freely turn therein in more than one plane; a passageway for a rope through said movable member at a 130

point eccentric to the axis of said movable member; guides for said passageway comprising a grooved sheave provided with proper bearings and turnable within said movable member and having an axis parallel with one of the axes of the said movable member and acting as a guide sheave, and another sheave within said movable member disposed in approximately the same plane as the first sheave and purposed to act as a ¹⁰ load sheave for a rope for the purpose specified and set forth.

VERNON F. JEWETT.
